UNITED STATES PATENT OFFICE.

JOSEPH H. YOUNG, OF NORTHAMPTON, MASSACHUSETTS.

FLIER FOR SPINNING-FRAMES AND TWISTING-FRAMES.

No. 828,010.

Specification of Letters Patent.

Patented Aug. 7, 1906.

Application filed May 5, 1905. Serial No. 258,972.

To all whom it may concern:

Be it known that I, JOSEPH H. YOUNG, a citizen of the United States of America, residing at Northampton, in the county of 5 Hampshire and Commonwealth of Massachusetts, have invented a new and useful Flier for Spinning-Frames and Twisting-Frames, of which the following is a specification.

My invention relates to improvements in 10 devices associated with the spools of either spinning or twisting frames for silk, cotton, flax, linen, &c., one such device being mounted above the spool on each spindle of the machine to receive and guide the thread after it 15 leaves the spool and to assist in the twisting operation.

My device comprises a frame of peculiar construction on a suitable carrier, such frame being provided with either one or two arms 20 with an eye or eyes therein and having an eye or eyes at the top and being bent and twisted into shape and caused to maintain its shape by means of rings, as hereinafter set forth. The frame is loose on the carrier. The carrier 25 may be made of wood, metal, or any other material suitable for the purpose, while the frame and rings are preferably formed of wire.

The object of my invention is to provide a 30 light and sensitive but durable device of the class specified which is comparatively inexpensive, easily handled, and entirely practicable and efficient in every particular. I attain this object by the means illustrated in 35 the accompanying drawings, in which—

Figure 1 is an elevation of a double-arm flier embodying my invention; Fig. 2, an elevation of a similar flier, except that there is only one arm; Fig. 3, a plan view of one of the 40 rings employed to form the hubs of the frame; and Fig. 4 an elevation, reduced, of the double-arm flier shown mounted on a spindle above the spool, the lower part of said spindle being broken off.

Similar letters refer to similar parts 45 throughout the several views.

Referring to the drawings, it will be observed that a carrier *a* is provided, upon which is loosely mounted a skeleton frame *b*. 50 This carrier has a tapered passage *c* extending longitudinally through the same to receive a spindle of the machine, as will be more fully explained hereinafter, and said carrier is provided at the ends with upper

and lower bearings *d*, upon which the frame *b* 55 is journaled. When the carrier *a* is made of wood, the bearing portions thereof should be bound with metal to better withstand the wear of the frame-hubs. The shape of the carrier between the bearings *d* is not of great 60 importance, except that the body of the carrier adjacent said bearings should be larger than the bearings themselves, so that the frame cannot fly off of the carrier, and of such shape as to permit of free rotation or independent action of one member without the other. My carrier is really a combined flier-block and mill-nut.

The frame *b* is provided with two hubs *e*, 70 adapted to be mounted on the bearings *d* of the carrier *a*, and has either one or two arms *f* with an eye *g* in the outer end of each, such arm or arms springing from the lower part of said frame and the eye or eyes *h* at the top. Of course the shape of the frame, with its 75 arms, may vary considerably; but when formed out of a single wire, as illustrated in the drawings, and mounted on such a carrier as is there shown the outlines therein appearing are very satisfactory. The hubs *e* 80 are loose on the bearings *d*, thus enabling the frame to remain stationary while the carrier revolves or to be rotated in an opposite direction to that of the carrier.

The hubs *e* consist of independent rings, 85 preferably having offsets *i* in opposite sides thereof (best shown in Fig. 3) to receive the adjacent portions of the frame, and in any event the rings must be soldered or otherwise fastened to or connected with contiguous 90 parts of the frame in such a manner that they cannot move up and down thereon.

In practice the flier operates with a spool, both the carrier of the flier and the spool being mounted on a revoluble spindle and rotating therewith. In Fig. 4 the upper part of a tapered spindle *k* is shown, upon which a spool *l* is mounted, and above said spool is the flier. Thread *m* is wound on the spool, and one end of the thread is led from the 100 spool up through the eye *g* in one of the arms *f* and through the associated eye *h* and thence to another section or mechanism of the machine to which belongs the mechanism just described. Both the spool *l* and the carrier 105 *a* are tight on the spindle *k* and revolve therewith, as already noted, and the frame *b* is normally rotated by reason of the frictional

contact between the same and its carrier and the force exerted by the thread which passes through certain of the eyes in said frame. When, however, it is desired to stop the flier 5 for any reason while the machine is running, said flier can be grasped by the hand and held stationary as long as may be necessary. This handling of the flier is often required when a thread breaks in order to rethread the 10 flier, or, in other words, to pass the broken end of the thread through the lower and upper eyes on one side thereof.

The double-arm construction as compared 15 with the single-arm construction not only preserves a more even balance, thus facilitating freedom of rotation, but affords better means for grasping the flier with the hand and always presents an eye at the bottom for the 20 thread regardless of whichever side of the frame is seized.

It will be obvious to one skilled in the art 25 that my flier may be changed more or less to adapt it to different machines and for different uses, all without departing from the nature of my invention.

What I claim as my invention, and desire to secure by Letters Patent, is—

1. The combination, in a flier, with a carrier adapted to be tightly mounted on a spindle and provided with end bearings, of a two-sided frame having eyes for thread and bends adjacent to such bearings, and independent rings forming hubs for said bearings, such rings being connected with and confining the sides of the frame at the bends therein. 30

2. The combination, in a flier, with a carrier adapted to be tightly mounted on a spindle and provided with end bearings, of a frame having eyes for thread, and independent rings forming hubs for such bearings, 40 such rings having oppositely-disposed offsets adapted to receive the sides of the frame and to be connected therewith.

In testimony whereof I have signed my name to this specification in the presence of 45 two subscribing witnesses.

JOSEPH H. YOUNG
